UNITED STATES PATENT OFFICE.

ERASMUS W. ALLEN, OF SENECA, KANSAS.

WASHING APPARATUS.

SPECIFICATION forming part of Letters Patent No. 335,413, dated February 2, 1886.

Application filed August 3, 1885. Serial No. 173,412. (No model.)

To all whom it may concern:

Be it known that I, ERASMUS W. ALLEN, a citizen of the United States, residing at Sene-
5 ca, in the county of Nemaha and State of Kan-
sas, have invented certain new and useful Im-
provements in Washing Apparatus; and I do
hereby declare the following to be a full, clear,
and exact description of the invention, such
as will enable others skilled in the art to which
10 it appertains to make and use the same.

The invention in this case relates to wash-
ing apparatus.

The object is to produce a washing appara-
tus or so-called "washing-machine" which
15 shall be of simple and ready construction and
efficient in use.

The invention consists, generally, in a box,
tub, or tank provided with inward projections
at its ends and sides, in combination with a
20 horizontal vertically-oscillating shaft having
attached to and projecting into the box from
it rigid loops or fingers.

The invention consists, specifically, in cer-
tain details of construction, which will be here-
25 inafter particularly pointed out.

In the accompanying drawings, forming part
of this specification, like letters of reference
indicate corresponding parts.

Figure 1 is a perspective view of the im-
30 proved washing apparatus, showing the out-
side of the same. Fig. 2 is a vertical longi-
tudinal section of the improved washing ap-
paratus, showing the interior. Fig. 3 is a de-
35 tail view of the loops, showing their manner
of attachment to and arrangement upon the
shaft, the dotted lines showing the inward bend
of the wires.

A designates the suds box or tub. This box
may be of any suitable material, shape, and
40 size, and is provided on its inside with pro-
jections or ridges. I prefer to construct the
box of a combination of metal—such as tin or
galvanized iron—and wood, the metal forming
45 the box proper and the wood forming pro-
jections or ridges *a* and *a'*, longitudinal braces
b and *b'* at the top and bottom, respectively,
cross-braces *c* and *c'* at the top, standards *d* at
the corners of one end, and a projecting
50 board, *e*, at the other end, the ridges *a* being
arranged horizontally across the ends on the
inside, while the ridges *a'* are arranged verti-
cally at the sides thereof; but the sides and

ends may be entirely of wood, there being a
metal bottom extending high enough to pro-
55 tect the wood. The projecting end of the board
e serves for attachment of the wringer or for
a rest for the operator. Where the suds-box
is in part of an outer casing and in part of an
inner rack or frame, the latter may be remov-
60 able for drying and cleaning. I have shown
only one ridge or projection at each end and
one at each side; but it is apparent that there
may be any suitable number.

It is well to construct the box with down-
ward inclined or convergent sides, by which
65 construction nearer approach to the box or
tub is permitted, and by which construction,
also, as is well known, the water is not so
easily splashed over the edges as in boxes or
tubs which have vertical sides.

The suds-box may rest directly upon a stove
or over a heater of any kind, thus taking the
70 place of an ordinary boiler; or it may rest up-
on the ground or floor or upon a suitable stand,
or may be supported upon feet or upon roller
75 attachments capable of being made rigid when
desired.

The suds-box is provided with a suitable
cover, *B*, which in the present instance is, like
the suds-box, constructed of wood and suit-
80 able metal. Crosswise in the cover, and jour-
naled therein at its ends, is a shaft, *F*, the re-
duced ends of which enter proper openings in
the cover, in which it has its bearings, and to
which are attached wooden pins or rigid loops
85 or wires *f*. These loops are of a material—
such as galvanized wire or coated or protected
wire—which will not rust and stain the clothes,
and in the present example are constructed
and are applied to as well as arranged upon
90 the shaft in a peculiar manner. There may
be any number of loops; but I have shown
the shaft here as carrying five, two being
arranged at each end and one centrally. Each
loop here consists of a long piece of wire bent
95 upon itself, the bow thus formed being then
twisted upon itself about half a turn, as shown
at *f'*, and having its free ends, near their ex-
tremities, bent horizontally inward, or first
horizontally outward and then vertically over
100 or downward to a position about parallel with
their respective sides of the wire composing
the loops. The end loops upon the shaft have
the single horizontal bend at their ends. The

central loop upon the shaft has the vertical as well as the horizontal bend at its ends.

The end loops are attached near the ends of the shaft in pairs, as follows: The inward-bent

- 5 ends of one loop are inserted into holes in the shaft or are driven into the shaft in such manner that the loop, when the shaft is stationary at its center of oscillation, will project obliquely downward, and, say, forward, and 10 the loop is then secured to the shaft by staples, which are driven over the legs of the wire forming it, near the end thereof, while the inward-bent ends of the other loop are inserted into holes in the shaft or are driven into the 15 shaft in such manner that the loop, when the shaft is stationary at its center of oscillation, will project obliquely downward and, say, backward, one leg of each loop—its inner leg—being about centrally between the legs of the 20 other, and the outer legs nearly embracing the shaft.

The central loop is attached to the shaft as follows: The vertically-bent ends of the loops are inserted into holes in the shaft or are 25 driven into the shaft in such manner that the loop, when the shaft is stationary at its center of oscillation, will project vertically downward and in such manner that this horizontal bend will be flush upon or countersunk in the 30 shaft, whereupon the loop is secured to the shaft by staples driven over the horizontal bends.

When the cover is in position, the loops will extend nearly to the bottom of the suds-box, 35 and by the twist they are so arranged that they present oblique or feathering edges in the direction of their motion—that is to say, no loop presents one edge or its flat side to either end, or has the parts of wire composing it parallel 40 either with the ends or sides. This is to exert a stirring action upon or give circulation to the material operated upon, and to enable the loops more readily to free themselves or shed it. I have shown the central loop arranged 45 at right angles to the others, which produces a stirring action within the area of the loops.

To oscillate the shaft, the same is provided with the lever-handle C, which projects upward through a slot in the cover and is fixed 50 in a slide, B', which moves in suitable ways or under bands or straps E.

Instead of locating the oscillating shaft in the cover, it may be directly in the suds-box, in which case the slot in the cover would be 55 large enough to allow the cover to be removed without disturbing the operating-lever; or the lever might be removed from the shaft to let the cover be removed. On the score of convenience and utility, however, the construc-

tion shown is greatly to be preferred, and it 60 will be seen that by my invention a very simple, compact, convenient, and useful apparatus is presented.

The operation will readily be understood. The articles to be washed are placed in the 65 box or tub, together with soap and water in suitable quantities, the cover which carries the oscillating shaft, loops, and lever-handle is put on, and the lever-handle being moved back and forth oscillates the shaft, which reciprocates the loops, causes agitation of the contents of the tub, and circulates the articles and causes them to rub against the projections or ridges, thus effectually cleansing them. As 70 already said, the position and twist of the 75 loops serves to cause the desirable motion of the clothing in the box, and it also causes, in connection with the articles therein, a very desirable stirring and circulation of the water or cleansing medium contained. The reciprocation of the loops may be carried on while the suds-box is subjected to heat, thus getting the assistance of the steam and boiling water. When the articles have been sufficiently 80 cleansed, the water is drawn off through a 85 suitable spigot or opening, fresh water may be put into the box, and the lever-handle then be operated to rinse them. The clothes may then be raised from the box or tub and wrung at its end.

The internal circulation between the loops, as well as the general circulation, is very efficient in the rinsing operation.

Having thus described my invention, what I claim, and desire to secure by Letters Patent, 95 is—

1. In combination with a shaft capable of oscillating, the loops or fingers f, twisted as described.

2. In combination with a shaft capable of 100 oscillating, the loops or fingers f, twisted as described, bent at their free ends, applied to the shaft by insertion of their ends therein, and one secured there by staples, substantially as described.

3. In combination with a suds-box having 105 horizontal and vertical projections and ridges on its inside, an oscillating shaft carrying twisted loops or fingers, whereby the material or articles to be washed may be agitated or circulated, and will be rubbed against the projections, substantially as described.

In testimony whereof I affix my signature in presence of two witnesses.

ERASMUS W. ALLEN.

Correction in Letters Patent No. 335,413.

It is hereby certified that in Letters Patent No. 335,413, granted February 2, 1886, upon the application of Erasmus W. Allen, of Seneca, Kansas, for an improvement in "Washing Apparatus," an error appears in the printed specification requiring correction, as follows: In line 104, page 2, the word "one" should be omitted; and that the Letters Patent should be read with this correction therein that the same may conform to the record of the case in the Patent Office.

Signed, countersigned, and sealed this 9th day of February, A. D. 1886.

[SEAL.]

H. L. MULDROW,
Acting Secretary of the Interior.
